SPEED WRENCH

Frank L. Fulke, Terre Haute, Ind.

Application August 2, 1950, Serial No. 177,210

11 Claims. (Cl. 81—58.3)

1

My invention relates to socket wrenches and particularly to speed wrenches of a type permitting rapid turning of a nut without removing the socket from the nut.

A prime object of the invention is to provide a speedy wrench that will not have any triggers or latches requiring thoughtful preliminary adjustment each time it is desired to change the direction of pull on the wrench, whether to screw in or unscrew the nut.

A further object is to provide for giving a powerful pull on the wrench, in either direction, merely by a short preliminary forward jab of the handle.

A further object is to provide for giving a powerful pull on the wrench, in either direction, by merely a preliminary twist of the handle under such circumstances as would make this preferable to a forward jab of the handle.

A further object is to provide for quickly meshing a pair of serrated surfaces which serve as a positive clutch, that cannot slip except by directly shearing a very substantial mass of hardened alloy steel, requiring many tons of pressure.

A further object is to provide for convenient, accurate, and very economical manufacture of my wrench.

A further object is to provide for each part of the wrench to be so strong that it will be impossible to apply, by human strength, sufficient stress to cause damage, without making the wrench heavy, bulky, or cumbersome to handle.

A further object is to provide simple and positive means to adjust the elements of the wrench for exactly correct mutual cooperation.

A further object is to reduce the lost motion of wrench required to engage its clutch—in other words reduce the usual 10 to 15 degrees of pivotal movement necessary with conventional ratchet wrenches before the wrench starts pulling.

These and other objectives may readily become apparent from the following description and reference to the drawings in which:

Fig. 1 is a side elevation of my improved wrench.

Fig. 2 is a view of the forward end of the wrench handle.

Fig. 3 is a magnified fragmentary view of a portion of Fig. 1.

Fig. 4 is a cross section of Fig. 3 taken on line A—B.

In Fig. 1 it will be noted that any desired size of detachable socket 1 may be propelled by a square driving lug 2 projecting from a disc-like structure 3 which has a central stem or shaft 4 and a serrated face 22 facing away from lug 2.

2

A hardened disc 9 has a conically beveled inner surface 6, a flat inner surface 17, and a notch 5 in its outer surface adjacent its central threaded bore. Disc 9 is threadedly adjusted on shaft 4 and then locked non-rotatively thereto.

A block 7 is bored at 10 for swiveling upon shaft 4, and right angle to bore 10 there is a bore 11 taking into the bore 10.

A handle 12, preferably knurled, is movably supported in bore 11, and it may rotate therein, or it may be thrust axially therein.

A surface 8 of block 7 which faces toward socket 1 is serrated similarly to serrated surface 22, and a compression spring 13 lying in a recess 24 constantly urges these two serrated surfaces to remain apart, so block 7 may swivel on shaft 4. The handle 12 is round, and at its inner end is flattened as at 14, and is further and more deeply flattened at 18, and is peripherally grooved at 20.

A wide flat spring 19 secured to block 7 by a screw 21 bears against flat surface 18 and provides central rotative bias for handle 12, however if the handle is turned considerably the spring 19 will ride into groove 20, whereby it will be noted that the rearward axial movement of handle 12 is at all times limited by spring 19 so that the handle cannot dislodge from its bore 11. Forward axial movement of handle 12 is limited by the abutment of its forward end against a side of shaft 4.

If handle 12 is pushed forward, the edge 15 of flattened surface 14 will slip along the conically beveled surface 6 of disc 9, and thereby force block 7 to move toward socket 1, contrary to the urge of spring 13, until flattened surface 14 of the handle 12 rides onto the flattened surface 17 of disc 9, at which time the socketward movement of block 7 ceases. At this time the two serrated surfaces 8 and 22 will have just completely meshed, so that a powerful pull may then be given handle 12 to rotate the socket 1 in either direction desired. As soon as this pull is completed handle 12 is jerked backward, whereupon spring 19 will disengage the serrated surfaces so that block 7 may swivel upon shaft 4 while the handle is moved to either the right or the left to obtain another "hitch." It will be noted that when the flat surfaces 14 and 17 are abutting, they are in a purely compressive relation, whereby any loosening or slippage of the meshed serrated surfaces, by reason of thrust resulting from angularity of the individual serrations, is completely blocked, regardless of any

50 55

human force that can be exerted upon handle 12 to turn socket 1.

The disc 9 is threadedly adjusted so that axial movement of handle 12 is barely possible when the serrated surfaces are completely meshed, then the disc 9 is locked by meshing thread at the end of shaft 4 over into notch 5 of disc 9.

The serrations 22 and 8 may optionally be meshed, and locked in mesh, by rotative movement of handle 12. By reason of the bias of spring 19, the middle point at the edge 15 of flattened surface 14 indicated by arrow 23 normally is in engagement with the conical surface 6, however if handle 12 is rotated about one-sixth turn, this point of engagement will shift to a point indicated by arrow 16. During this rotary movement of the handle of course block 7 will be crowded toward the socket 1 until the serrated surfaces 22 and 8 are meshed, it being understood that the coating surfaces, and particularly flattened surface 14 are sized to accomplish this. Since axial retraction of the handle is blocked by spring 19 in groove 20, it will be seen that a compressive relation exists to lock the serrations in mesh when surface 6 of disc 9 contacts the point indicated by arrow 16.

In the operation of my wrench, socket 1 is placed over the nut to be turned and with the handle held rather loosely a quick forward jab (or a twist) meshes the serrations solidly together, ready for as hard a pull upon the handle as desired, in either direction desired, and at the completion of this pull the handle is jerked backward (or twisted) so that the handle may swivel on shaft 4 without turning the socket 1 for obtaining another "hitch" to repeat the pull.

I have contrived my wrench particularly for heavy duty work, where ordinary types such as pawl-and-ratchet have not the strength to stand all the stress a man can exert at the end of a long handled wrench, such as with set screws in coal cutting chains, or cap screws securing heavy truck wheels. The stress necessary to shear off all the serrations of hardened steel may be calculated in tons of pressure, far beyond man's strength.

There are no triggers or latches requiring careful preliminary settings or adjustments for changing the direction of the working pull on the wrench. There is no danger of breaking or distorting any of the parts which are few in number and very economical to manufacture. The disc 9 is case-hardened, and the corner 15 of flattened handle surface 14 is preferably an overlay of Stellite or boron hard metal, ground to size. These are the principal points of wear, however the wear is distributed evenly upon the inner surfaces of disc 9, not concentrated. The driving element 3 with its stem 4 is preferably an upset forging, while block 7 is a drop forging, and the identical serrations 22 and 8 may be coined upon these forgings by a single coining die.

Since the identical serrations on my two clutch elements may be quite small and therefore of a very large number as, for example 90 serrations upon each, the pivotal movement of the wrench that is lost before the clutch engages is extremely small, as compared with a ratchet wrench loss of about 15 degrees, therefore it will be preferable for operation in very limited space.

I claim:

1. In a device of the class described, a stem, a block mounted for rotation about the axis of said stem, interengageable means fixed relative to said stem and to said block, respectively, and rela-

tively movable, in the direction of said stem axis, into and out of cooperative relation, a handle movably carried by said block and projecting substantially radially relative to said stem axis, and cam means on said handle and on said stem, said cam means cooperating, upon adjustment of said handle relative to said block, to effect relative axial movement of said interengageable means.

2. In a device of the class described, a stem, a block mounted for rotation about the axis of said stem, interengageable means fixed relative to said stem and to said block, respectively, and relatively movable, in the direction of said stem axis, into and out of cooperative relation, a handle carried by said block and projecting substantially radially relative to said stem axis, said handle being reciprocable relative to said block toward and away from said stem axis, a cam element carried by said stem, and means moving with said handle and cooperating with said cam element, as said handle moves toward said stem axis, to effect relative axial movement of said interengageable means.

3. In a device of the class described, a stem, a block mounted for rotation about the axis of said stem, interengageable means fixed relative to said stem and to said block, respectively, and relatively movable, in the direction of said stem axis, into and out of cooperative relation, a handle carried by said block and projecting substantially radially relative to said stem axis, said handle being oscillable about its own axis, relative to said block, an abutment element carried by said stem, and cam means moving with said handle and cooperating with said abutment element, upon oscillatory movement of said handle, to effect relative axial movement of said interengageable means.

4. In a device of the class described, a stem, a block mounted for rotation about the axis of said stem, said stem and said block being relatively axially movable, a clutch element fixed relative to said stem, a clutch element fixed relative to said block, spring means resiliently urging separation of said clutch elements, a handle movably carried by said block and projecting substantially radially relative to said stem axis, and cam means on said stem and on said handle, respectively, said cam means cooperating, upon adjustment of said handle relative to said block, to force said clutch elements, against the tendency of said spring means, into driving engagement.

5. In a device of the class described, a stem, a block mounted for rotation about the axis of said stem, said stem and said block being relatively axially movable, a clutch element fixed relative to said stem, a clutch element fixed relative to said block, spring means resiliently urging separation of said clutch elements, a handle carried by said block for reciprocation relative to said block toward and away from said stem axis, a cam element fixed to said stem and having a coned face presented toward said stem, clutch element, said block and handle being interposed between said cam element and said stem clutch element, and means moving with said handle and engageable with said cam element, upon movement of said handle toward said stem axis, to force said clutch elements, against the tendency of said spring means, into driving engagement.

6. The device of claim 5 in which said cam element is provided, further, with a holding surface, substantially normal to said stem axis, at the apex of said coned face, said means moving

with said handle being engageable with said holding surface, at the limit of its movement toward said stem axis.

7. In a device of the class described, a stem, a block mounted for rotation about the axis of said stem, said stem and said block being relatively axially movable, a clutch element fixed relative to said stem, a clutch element fixed relative to said block, spring means resiliently urging separation of said clutch elements, a handle carried by said block for oscillation about its own axis relative to said block and projecting substantially radially relative to said stem axis, and an abutment member carried by said stem, said handle being provided with a cam surface eccentric to said handle axis and engageable with said abutment member, upon oscillatory movement of said handle, to force said clutch elements against the tendency of said spring means, into driving engagement.

8. In a device of the class described, a stem, a block mounted for rotation about the axis of said stem, said stem and said block being relatively axially movable, a clutch element fixed relative to said stem, a clutch element fixed relative to said block, spring means resiliently urging separation of said clutch elements, a handle carried by said block for reciprocation and oscillation relative to said block upon its own axis, said handle projecting substantially radially relative to said stem, a coned abutment member coaxially carried by said stem, said block and said handle being interposed between said stem clutch element and said abutment member, and cam means moving with said handle and cooperating with said abutment member, upon oscillatory movement of said handle or reciprocatory movement thereof toward said stem axis, to force said clutch elements, against the tendency of said spring means, into driving engagement.

9. The device of claim 8 in which said handle is formed with a longitudinally-extending notch bounded by shoulders at its opposite ends, and a finger fixed to said block, extending into said notch and cooperating with said shoulders to limit reciprocatory movement of said handle relative to said block.

10. The device of claim 9 in which said handle is further formed with a peripheral groove adjacent said cam means, said finger being engageable in said groove, at times upon rotational movement of said handle, to restrain said handle against reciprocation.

11. The device of claim 8 in which said handle is formed with a peripheral groove adjacent said cam means, and a finger fixed to said block with its free end in registry with said groove, said finger being engageable in said groove, at times upon rotational movement of said handle, to restrain said handle against reciprocation.
